(57) **CLAIM**

The ornamental design for a light fixture, as shown and described.

DESCRIPTION

FIG. 1 is a bottom perspective view of the light fixture according to my new design.

FIG. 2 is a side view of the light fixture shown in FIG. 1.

FIG. 3 is an opposite side view of the light fixture shown in FIG. 1.

FIG. 4 is a bottom view of the light fixture shown in FIG. 1; and,

FIG. 5 is a bottom view of the light fixture according to a second embodiment of my new design, which is identical to the first embodiment except for the absence of the circular opening on the bottom surface thereof.

1 Claim, 4 Drawing Sheets
